US0D1063891S

(12) **United States Design Patent** (10) **Patent No.:** **US D1,063,891 S**
(45) **Date of Patent:** **** Feb. 25, 2025**

(54) **PLAYBACK DEVICE**

(71) Applicant: **Sonos, Inc.**, Santa Barbara, CA (US)

(72) Inventors: **Stefan Reichert**, Santa Barbara, CA (US); **Mieko Kusano**, Santa Barbara, CA (US); **Roland Bird**, Eindhoven (NL); **Roger Swales**, Eindhoven (NL); **Niels van Hoof**, Eindhoven (NL); **Lukasz Natkaniec**, Munich (DE); **Dana Krieger**, Santa Barbara, CA (US); **Tadeo T. Toulis**, Santa Barbara, CA (US); **Mike Chamness**, Santa Barbara, CA (US); **Hilmar Lehnert**, Santa Barbara, CA (US); **Wilfred Wei**, Shanghai (CN); **Wei Hean Liew**, Boston, MA (US)

(73) Assignee: **SONOS, INC.**, Goleta, CA (US)

(**) Term: **15 Years**

(21) Appl. No.: **29/783,365**

(22) Filed: **May 12, 2021**

Related U.S. Application Data

(63) Continuation of application No. 29/641,066, filed on Mar. 19, 2018, now Pat. No. Des. 934,199, which is

CLAIM

The ornamental design for a playback device as shown and described.

DESCRIPTION

FIG. 1 is a front view of a playback device, according to our new design;

FIG. 2 is a rear view thereof;

FIG. 3 is another rear view thereof;

FIG. 4 is a top view thereof;

FIG. 5 is a bottom view thereof;

FIG. 6 is a left side view thereof;

FIG. 7 is a right side view thereof;

FIG. 8 is a perspective view thereof;

FIG. 9 is another perspective view thereof;

FIG. 10 is another perspective view thereof;

FIG. 11 is an enlarged perspective view thereof, showing an isolated portion of the article; and,

FIG. 12 is an interior view of a playback device according to our new design.

The broken lines illustrate portions of the article that form no part of the claimed design.

1 Claim, 12 Drawing Sheets

Related U.S. Application Data

a continuation of application No. 29/627,445, filed on Nov. 27, 2017, now Pat. No. Des. 855,587, which is a continuation of application No. 29/577,674, filed on Sep. 14, 2016, now Pat. No. Des. 806,678, which is a continuation of application No. 29/525,027, filed on Apr. 25, 2015, now Pat. No. Des. 768,602.
